**BRACKET FOR TANK TYPE VACUUM CLEANERS
OR SIMILAR ARTICLE**

Thomas R. Symington, 333 E. 53rd St.,
New York, N.Y. 10022

Filed Feb. 20, 1969, Ser. No. 15,858

Term of patent 7 years

Int. Cl. D8—03

U.S. Cl. D8—233

FIG. 1 is a view in perspective of a bracket for tank type vacuum cleaners or similar article showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and

FIG. 7 is a rear elevational view thereof.

I claim:

The ornamental design for a bracket for tank type vacuum cleaners or similar article, substantially as shown.
